[57] CLAIM

The ornamental design for a device for an air freshener housing, substantially as shown.

DESCRIPTION

FIG. 1 is a perspective view of an air freshener housing showing my new design;

FIG. 2 is a top plan view thereof;

FIG. 3 is a left side elevational view thereof, the right side being a mirror image of the left side shown;

FIG. 4 is a front elevational view thereof;

FIG. 5 is a rear elevational view thereof; and

FIG. 6 is a bottom plan view thereof.

FIG. 2

FIG. 4
